PAGE 3

Fig. 1 is a view in side elevation of a combined tractor and loader embodying our new design;

Fig. 2 is a similar view of the opposite side of the tractor mounted loader;

Fig. 3 is a rear elevation of the same;

Fig. 4 is a front elevation of the same;

Fig. 5 is a plan view of the same.

The essential features of our design reside in those portions shown in full lines.

We claim:

The ornamental design for a combined tractor and loader, substantially as shown and described.
